UNITED STATES PATENT OFFICE.

EDWIN V. MUNDY, OF DULUTH, MINNESOTA, ASSIGNOR OF ONE-FOURTH TO
HARRY C. CRAWFORD, OF SAME PLACE.

DESIGN FOR A BOOT AND SHOE CALK.

SPECIFICATION forming part of Design No. 15,490, dated October 28, 1884.

Application filed July 19, 1884. Term of patent 14 years.

To all whom it may concern:

Be it known that I, EDWIN V. MUNDY, of Duluth, in the county of St. Louis and State of Minnesota, have invented and produced a new and original Design for a Boot and Shoe Calk, of which the following is a full, clear, and exact description.

My design for a boot and shoe stud or calk consists in a pointed head of conical configuration mounted on the frustum of a cone having a reverse taper to the pointed portion of the head, and surmounted in its turn by a tapering extension or shank shaped to represent a screw tapering upward, as herein shown and described.

Reference is to be had to the accompanying drawing, forming part of this specification, which represents a longitudinal view, upon an enlarged scale, of a boot or shoe calk embodying my design.

The lower portion, *a*, of the head of the calk terminates in a point below, and is of conical configuration, and its upper portion, *b*, is in

the shape of the frustum of a cone tapering in a reverse direction to the lower portion, *a*, from the outer margin of the head of the said portion.

c indicates the shank of the calk, which is made to represent an upwardly-tapering screw mounted on the frustum of a cone, *b*, and terminating in a point at top.

I claim—

The within-described design for a boot and shoe stud or calk, which consists in a head, the lower portion, *a*, of which terminates in a point and has the form of a true cone, and its upper portion, *b*, in the form of the frustum of a cone tapering in a reverse direction to the lower portion, *a*, and having mounted on it a shank, *c*, shaped to represent a tapering screw terminating in a point above, as shown.

EDWIN V. MUNDY.
